UNITED STATES PATENT OFFICE

119,085

DESIGN FOR AN ELECTRIC LAMP UNIT

Samuel M. Dover, Chicago, Ill.

Application September 21, 1938, Serial No. 80,017

Term of patent 3½ years

To all whom it may concern:

Be it known that I, Samuel M. Dover, a citizen of the United States, residing at Chicago, in the county of Cook and State of Illinois, have invented a new, original, and ornamental Design for an Electric Lamp Unit, of which the following is a specification, reference being had to the accompanying drawing, forming a part thereof.

In the drawing:

Figure 1 is a front view of an electric lamp unit embodying my new design, the light bulb and lens shown in Figures 2 and 3 being omitted;

Figure 2 is a side view of the electric lamp unit;

Figure 3 is a top view thereof; and

Figure 4 is a sectional view taken along the line 4—4 of Figure 2 and looking in the direction of the arrows.

I claim:

The ornamental design for an electric lamp unit, as shown and described.

SAMUEL M. DOVER.
